UNITED STATES PATENT OFFICE.

EMILE POULIN, OF CENTRAL FALLS, RHODE ISLAND.

CIRCUIT CLOSER.

Application filed December 16, 1926. Serial No. 155,202.

This invention relates to circuit closers, and particularly to a door operated circuit closer.

This invention comprehends the provision 5 of an improved door operated circuit closer, particularly adapted for use in refrigerators and the like, so that the first opening of the door will operate a switch to close and energize a light circuit in the refrigerator which 10 will remain energized upon the closing of the door, and which upon the subsequent opening of the door, will operate the switch to open the light circuit so that the same will remain open upon closing of the door and 15 be reset for the closing of the circuit in the following opening movement of said door, in order that the refrigerator or other chamber may be entered for the removal of material and upon leaving lights in the chamber 20 will be extinguished, eliminating the necessity of operating a switch in entering and leaving the refrigerator or other chamber for controlling the light.

The invention more particularly comprehends the provision of a special circuit closer construction and operating mechanism adapted for association with a door so that successive opening movements of the door 25 will alternately operate the circuit closer to alternately close and open the circuit controlled thereby through the special construction and operation of the circuit closer and its operating mechanism.

The invention comprehends numerous objects residing in the specific construction and association of the parts for carrying out the invention which are more particularly pointed out in the following detailed description and in the claims directed to a preferred 40 form of the invention, it being understood however, that various changes in the size, shape and relation of the parts may be made without departing from the spirit and scope of the invention as herein set forth.

In the drawings forming part of this application:—

Figure 1 is an elevational view of a door and surrounding structure illustrating the switch mechanism of this invention applied thereto in operative position.

Fig. 2 is a sectional view taken on the line 2—2 of Fig. 1.

Fig. 3 is an opposite side elevation of the switch mechanism from that shown in Fig. 2.

Fig. 4 is a sectional view taken on the line 4—4 of Fig. 3.

Fig. 5 is a view similar to Fig. 3, with portions shown in longitudinal section and with the switch mechanism and associated parts in the position assumed when the switch is 60 closed for energizing the circuit controlled thereby.

Fig. 6 is a detailed horizontal sectional view taken on line 6—6 of Fig. 3, parts being 65 omitted, for the sake of clearness and illustration.

Fig. 7 is a perspective view of the primary operating lever.

While this invention is particularly designed for use in connection with refrigerators, it is to be understood that it may well be used in conjunction with any other entrance structure utilizing a door where it is desired to close the electric circuits to energize lights in a chamber, building, or the like which are extinguished upon leaving the building and opening and closing the door for the second time.

A chamber or refrigerator structure is indicated at 1 which has an opening closed by 80 the door 2, suitably hinged or otherwise supported as indicated at 3 in any usual and desired manner.

The present invention includes a switch structure having a support 4 in the form of a bracket with laterally extending portions 5 at the opposite ends thereof provided with feet 6 to secure the main body of the support in spaced relation to the structure 1 of the housing or refrigerator. An insulating 85 plate 7 is mounted on one end of the support 4 to which is secured a pair of spaced parallel posts 8 around which are coiled suitable conductor elements 9 having terminals 10 projecting laterally from the post and terminating in spaced overlapping relation as shown in Fig 4 which forms the terminals for an electric circuit which is to be controlled. The opposite ends of the coil wires 9 are extended through the insulating plate 100 7 and secured to suitable binding posts 11 mounted on the opposite corners of the plate member 7.

Between the binding posts 11, the plate member 7 is recessed as indicated at 12 and 105 through which extends the supporting bracket 13 having the laterally extending upper free ends which receive the screw 14 adapted to removably secure the cover 15 over the switch contacts 10. This cover 15 is 110 formed with a slotted portion 16 through which projects the slide member 17 slidably

mounted in the bifurcated end formed in the upwardly extending projections 18 of the guide plate 19.

The end of the slide member 17 projecting 5 into the housing 15 has an insulating block 20 secured thereto which projects upwardly within the casing cover and carries the movable contact member 21 on the upper end thereof which is adapted to engage between 10 the terminals 10 and close the electric circuit connected with said terminals, for retaining the slide member 17 in assembled relation for said guide plate.

This slide member 17 is adapted for limited 15 reciprocating motion in the bifurcated projections 18 and between said projections mounts a rod 23 to which is secured the coiled springs 24 at one end which are anchored at their opposite ends to the studs 25 secured 20 to one of the bifurcated projections 18 so as to normally operate the slide member 17 to move the contact 21 into disengaged relation relative to the terminals 10 and maintain the circuit controlled by said terminals de-energized. 25

The rod 23 projects through the opposite side of the slide member 17 and supports a roller 26 while a collar 27 is mounted on the rod to retain the latch member 28 against 30 the slide member shown in Fig. 6 and prevent lateral movement thereof on said rod. The free end of this latch member is provided with an enlarged head 29 projecting laterally relative to the main body of the latch 35 and adapted for locking cooperation with the bifurcated projection 18 on the guide plate 19, at the end of the supporting bracket 4 to retain the slide member 17 with the movable contact 20 engaged with the terminals 10 as 40 shown in Fig. 5, the shoulder formed at 30 cooperating with the projection 18 in retaining the movable contact engaged with the terminals 10 against the tension of the springs 24.

45 A coiled spring 31 is secured to the collar 27 and the latch member 28 for normally moving the head 29 toward the projection 18 on the guide plate and in the position of the parts as shown in Fig. 2, the end portion of the head 29 engages with the ends of the projection 18 for purposes which will presently appear. What may be termed the back of the latch member 28 is formed with an arcuate contour as indicated at 32 with which engages 55 the roller 33 carried by the primary operating lever 34 which is of L-shaped formation.

This operating lever 34 is pivotally mounted at the juncture of the angularly extending portion, on the angle bracket 35 removably secured to one of the projections 18 of the guide plate as shown in Fig. 5. This primary operating lever 35 has a short arm 36 provided at its free end with a pivotally mounted trip member 37 which is normally retained in a predetermined position by the

spring member 38 rotating the trip member on its pivot to engage the stop 39 carried on the operating lever.

This trip member 37 is adapted to engage the roller 26 on the slide member 17, and in 70 pivotal movement in one direction, will move the slide member for engaging the movable contact 21 between the terminals 10, while in the opposite direction of movement of the lever, the trip member 37 will ride over the 75 roller through rotation of the pivot against the tension of spring 38 in order that it will operate the slide member in one direction only.

In the reciprocation of the slide member 17, 80 between its opposite limits of movement, which may be ascertained from the section in Figs. 3 and 5 respectively, the position of the latch member 28 controls the position of the primary operating lever on the bracket 85 35 through engagement of the arcuate surface 32 with the roller 33, the primary operating lever being normally rotated in one direction to the positions shown in Figs. 3 and 5, by means of a suitable coiled spring secured to 90 the lever adjacent the pivotal mounting thereof at one end and at the opposite end to an annular plate member 40 carried by the pivot pin 41 mounted in the bracket 35 which carries the lever 34. This spring is illustrated in 95 Fig. 2 at 42.

The head 29 of the latch member and the free end of the long arm 43 of the primary operating lever 34 are each provided with trip members 44 and 45 respectively, which are 100 resiliently retained in the extended position as shown in Figs. 3 and 5 by suitable resilient means operating the trip members on their pivotal mounting, and which are adapted for engagement to operate the lever and latch in 105 one direction, while engagement with the trip in the movement in an opposite direction, will not operate the lever and latch but will permit of an operation of a trip member on their pivots to permit passage of the operating elements. 110

A bar member 46 is secured to the door 2 at one end and has the opposite end projecting beyond the upper edge thereof as shown in Fig. 1, carrying the operating element 47 which is adjustably connected thereto through the provision of the slot and bolt connection indicated at 48. The free end of the operating element 47 is provided with a crescent shaped head 49 having end portions 115 extended in angular relation to the body portion as illustrated in Fig. 2.

With the construction above described, the primary operating lever 34 will have the trip member 45 thereon projecting substantially 120 beyond the end of the trip member 44 on the latch 28, as shown in Fig. 3, when the movable switch member 21 is in disengaged relation with the terminal 10 for de-energizing 125 the circuit controlled thereby. In this position

tion of the parts as shown in Fig. 3, the operating elements 47 on the door as the head 49 thereon is in a position to engage the trip member 45 and in the opening movement of 5 the door from the position shown in Fig. 1, it will engage and operate this primary lever, while the trip member 44 on the latch member 28 will be withdrawn out of the plane of movement of the head 49.

10 This operation upon the opening movement of the door will rotate the lever 34 on its pivot and move the trip member 37 to engage roller 26 so that the slide member 17 will be moved to engage the movable contact 21 between the terminals 10 and close the circuit controlled thereby. Upon completion of the movement of the slide member 13 by the member 34, the latch member 28 will move beyond the end of the projection 18 so that 20 the shoulder 30 thereon will engage beyond the end of said projection and retain the slide member in the operated position with the movable contacts 21 engaged between the terminals 10.

25 The door is then moved to the full open position which permits the lever 34 to be moved toward the guide plate 19 by the action of the resilient member 42 and by reason of the change in position of the articulate surface on the latch member, due to the movement of the latch member toward the guide plate 19, the lever 34 will move on its pivot to a position as illustrated in Fig. 5, with the trip 45 retracted from the projected 35 position as shown in Fig. 3.

In this position of the parts as illustrated in Fig. 5, the latch member 28 is projected so that the trip member 44 thereon projects substantially beyond the trip member 45 on 40 lever 34 so that in the closing movement of the door, the head 49 of the operating element 47 will engage the trip member 44 and through the pivotal movement of said trip member, moves past the same without operating any portion of the switch mechanism.

45 Upon the next opening movement of the door, the head 49 of the operating element 47 will engage the trip member 44 again and will move the latch member to disengage the shoulder 30 from the end of the projection 18 so that the springs 24 will operate the slide member to return it to the position shown in Fig. 3, and thus disengage the movable contact member 21 from contact with the terminal 10 and thereby opening the circuit controlled by said terminals.

50 In addition to this operation, the pivotal movement of the latch member from the position shown in Fig. 5 to that shown in Fig. 3, and its inward movement by the actuation of the slide member will also move the lever 34 through the arcuate surface 32 engaging with the roller 33 and again cause the projection of the trip member 45 into the path of movement of the head 49 of the operating element.

55 It will thus be seen that in the subsequent closing movement of the door, the head will engage the trip and pivotally move the same on the lever while in the subsequent opening movement, the trip 45 will be again engaged 70 for operating the lever 34 and moving the movable contact member 21 into closed position.

60 From the above description it should be clearly understood that the primary operating lever and the latch member control the operative positions of one another so that only one of the trip members 44 and 45 which insure the operation of the lever and the latch member is projected into the path of the operating element carried by the door and that after either the latch member or the operating lever has been operated by the operating element on the door, it will move to an inoperative position and operate the other element, so as to move the trip member into operative position.

65 In this way, the opening and closing movement of the door will effect the operation of the movable contact member to close the circuit between the terminals 10 while the next opening and closing movement of the door will serve to permit the movement of the contact member to opening the circuit between the terminals 10, in this way providing a positive operation and control of the circuit closer formed by the terminals 10 and the movable contact member 21.

70 It will thus be seen that by connecting the light circuit in a refrigerator to this improved circuit controller, that upon entering the refrigerator the opening of the door will light the light, which will remain lighted after the same has been closed, during the time the refrigerator or other compartment is occupied, and upon the second opening and closing of the door in leaving the refrigerator or other compartment, the lights will be extinguished through de-energization of the circuit, and in this way eliminating the necessity of operating a switch upon entering and leaving the chamber.

75 While this device is designed for application especially to refrigerators, as above set forth, it is to be understood that it may as well be applied to any other building construction where the automatic control of illumination of the building or chamber is desired to be operated and extinguished upon the entry and exit therefrom.

80 A substantially novel switch construction has thus been provided in which the primary operating lever and the latch member cooperate in a highly novel manner for the relative control of each other in producing the operation of the circuit controller as above set forth.

85 Having thus described my invention, what I claim as new is:—

90 1. In combination, a support, a circuit 130

closer mounted on the support having a movable controlling element, a rectilinearly sliding member mounted on the support carrying said movable controlling element for the 5 circuit closer, an operating lever for said slide member, a latch member mounted on said slide member for retaining the same in one position of operation, resilient means normally adapted to operate the slide member 10 to retain it in another position of operation, and means for operating the lever and latch member in a predetermined manner for operating the slide member to close and open the control by said circuit closer in successive 15 operations of the last named means.

2. In combination, a support, a circuit closer mounted on the support having a movable controlling element, a rectilinearly sliding member mounted on the support carrying 20 said movable controlling element for the circuit closer, an operating lever for said slide member, a latch member mounted on said slide member for retaining the same in one position of operation, resilient means 25 normally adapted to operate the slide member to retain it in another position of operation, a trip member for said latch member disposed in the path of a moving object and ineffective for actuating the latch member 30 for releasing movement when engaged by said object in its movement in one direction

and arranged during its movement in the opposite direction for releasing the latch, whereby through the movement of the latch member to control said circuit. 35

3. In combination, a support, a circuit closer mounted on the support having a movable controlling element, a rectilinear sliding element mounted on said support and carrying said movable controlling element 40 for the circuit closer, an operating member for said slide member, a latch member mounted on said slide member for retaining the same in one position of operation, resilient means normally adapted to operate the slide 45 member to retain it in another position of operation, a trip member carried by said latch member and said operating member and disposed in the path of the moving object and adapted for latch releasing and lever 50 operating movement when engaged by said object in its movement in one direction and inactive during its movement in an opposite direction, whereby through the movements thereof to control said circuit and interengaging means between said operating lever and the latch adapted to actuate the former upon the releasing movement of the latch to move the latch lever into the path of said object. 55

In testimony whereof I affix my signature.
EMILE POULIN. 60
